Primary Examiner—Stella M Reid*Assistant Examiner*—Rashida C McCoy(74) *Attorney, Agent, or Firm*—Gifford, Krass, Sprinkle, Anderson & Citkowski, P.C.(57) **CLAIM**

The ornamental design for shoe, as shown and described.

DESCRIPTION

FIG. 1 is a top view of a shoe, showing our new design;

FIG. 2 is a side view thereof;

FIG. 3 is a bottom view thereof;

FIG. 4 is a front elevation view thereof; and,

FIG. 5 is a rear elevation view thereof.

The broken lines shown in the Figures are for environmental purposes only and form no part of the claimed design.
